UNITED STATES PATENT OFFICE.

VIRGIL BOGERT, OF NEW YORK, N. Y.

DESIGN FOR A BOX.

44,432.

Specification for Design.

Patented Aug. 5, 1913.

Application filed February 18, 1913. Serial No. 749,273. Term of patent 14 years.

To all whom it may concern:

Be it known that I, VIRGIL BOGERT, citizen of the United States, residing at New York, in the county of New York and State of New York, have invented a new, original, and ornamental Design for Boxes, of which the following is a specification, reference being had to the accompanying drawing, forming part thereof.

Figure 1 is a side elevation of a box, show-

ing my new design. Fig. 2 is a plan view thereof.

I claim:—

The ornamental design for a box, as shown.

VIRGIL BOGERT.

Witnesses:

MATT. J. BOGERT,
GEO. V. DEMOREST.
